HOLGER NIELSEN, OF BEAVER FALLS, PENNSYLVANIA, ASSIGNOR TO KEYSTONE REFRIGERATING CORPORATION, OF BEAVER FALLS, PENNSYLVANIA, A CORPORATION OF PENNSYLVANIA

ROTARY COMPRESSOR

Application filed June 16, 1928. Serial No. 286,035.

The invention aims to improve the construction and operation of rotary pumps, to adapt them for compressing gases to comparatively high pressures and to increase the 5 mechanical efficiency and improve the smoothness of operation of such pumps.

Rotary pumps having a cylindrical rotor with a blade or blades sliding through a slot in the rotor have been known for a number 10 of years. The rotor is usually mounted eccentrically in the bore of the pump body and the tips of the blades are made to touch the inside wall of the pump body while rotating therein. The gas tight contact of the blades 15 within the body is accomplished by various methods. Some manufacturers split the blade in halves and put springs in between the two half parts so as to continuously keep them out against the inside surface of the 20 pump body. The pump chamber will in this case be a circular cylinder. Other manufacturers make the blade in one solid piece and give the bore of the pump body such a shape as to always have a constant distance between 25 the two points where the blade touches, the chamber in such case being a cylinder of non-circular shape, advantageously conforming to the limaçon. A preferred form of pump of this nature having packing between the ends 30 of the blade and the chamber wall is described in Roessler Patents Nos. 1,114,046 and 1,649,- 256. Although rotary blade pumps of various types have, as a rule, given satisfaction for pumping liquids, and also for compressing 35 gases to a moderate rate of compression, there has always been some lack of satisfaction where a high compression ratio of gases was desired, because of a tendency for pulsations to be produced in the outlet passage and 40 pump chamber, decreasing the efficiency and smooth operation of the pump and unnecessarily heating the gases leaving the pump.

These disadvantages are overcome by the present invention, which may be applied to 45 rotary pumps of various types, as shown in the accompanying drawings, wherein two preferred forms of compressors for air or gases, having a high ratio between suction and discharge pressure, are shown for pur- 50 poses of illustration.

In the drawings

Fig. 1 is a longitudinal or axial section through a rotary blade pump of the spring pressed blade type on the section line 1-1 in Fig. 2; the rotor and blade being shown in 55 elevation;

Fig. 2 is a transverse section of the same on the line 2-2 in Fig. 1; and

Figs. 3 and 4 are views similar to Figs. 1 and 2 of a solid vane or rocker type of rotary 60 pump embodying the invention.

Referring to Figs. 1 and 2 the pump body 11 is provided with an inlet connection 12 and outlet connection 13 adapted for joining on to the suction pipe and delivery pipe of 65 the fluid pressure system. The pump body contains a chamber which may be cylindrical and which contains eccentrically mounted for rotation therein a cylindrical drum or rotor 14 provided with a transverse slot for the 70 blades 15 which are slidable therein and are normally kept pressed in close contact against the inner wall of the pump chamber by springs 16. The rotor is mounted in suitable bearings, and contacts with the side of the 75 chamber between the inlet port 17 and outlet port 18 to form a gas tight joint therewith. It also contains grooves or recesses 19 adjacent to the pressure side of the vanes at the outlet end of the pump chamber adapted to 80 register with the outlet port 18 periodically.

An oil port 20 is provided in the end wall of the pump chamber in position to be uncovered by the recesses 19 at about the beginning 85 of each compression period. The oil port is in communication with a suitable source of oil under sufficient pressure to permit a jet of oil to be shot into the pump chamber in advance of each blade for each rotation of the pump.

The pump chamber is provided with a port or passage 21 positioned near the outlet port 18 and furnished with a valve 22, normally held closed by springs or other suitable means, for relieving excessive pressure produced by liquid particles trapped in the pump chamber or otherwise. This valve may discharge 95 into any suitable outlet, such as the outlet passage 13 as shown.

The pump may be driven in the direction 100

of the arrow in Fig. 2 by a motor mounted on the rotor shaft, or by gearing from any suitable source of power. For small compressor units, the rotor is preferably driven at a speed of from fifteen to eighteen hundred revolutions per minute, but the speed will be controlled by the circumstances of use.

The rotation of the rotor and blades past the inlet port 17 draws in a charge of gas 10 into the space in the pump chamber between the rotor and blade as it moves away from the inlet port, and when the succeeding blade passes the inlet port this gas will be trapped in the chamber between the two blades, and 15 as the rotor continues to rotate it will be compressed in front of the following blade in the diminishing space as the blade approaches the outlet port 18 until the adjacent recess 19 uncovers the outlet port.

20 The size and relative location of the inlet and outlet ports, dimensions of the chamber and rotor, and size of the recesses 19 in the rotor, are chosen to suit the desired compression ratio and capacity of the pump at the 25 speed of rotation for which it is designed.

With the sizes and relative positions of the parts as illustrated, the blade will move through an angle of about 180° , compressing the gas gradually to a pressure corresponding 30 approximately to that in the outlet passage, before the recess 19 uncovers the outlet port 18, and permits discharge of the compressed gas from the pump chamber. This pressure in the illustrative example may be about 50 to 35 60 lbs. per sq. in. corresponding to a compression ratio of 4 or 5 to one. There is no tendency for pulsations to be produced in the outlet passage, because there can be no flow back into the pump chamber when the outlet port 40 is uncovered as would be the case with the ordinary types of rotary pumps having no means for closing the outlet passage until the proper compression pressure is attained in the pump chamber.

45 In the form of pump illustrated in Figs. 3 and 4, the casing 23, rotor 24 and inlet and outlet ports 25, 26, oil port 27, relief valve 28 and driving means are similar to the form illustrated in Figs. 1 and 2, but the rotor has a 50 solid blade 29 provided with rockers 30 at its ends bearing against the inside wall of the pump chamber, which is bored to conform to a cylinder of limaçon shape. The recesses 31 in the rotor function as described above to 55 uncover the outlet port 26 at the proper times to permit a smooth discharge, and prevent rush of gas back into the chamber from the outlet passages at all other times.

It is evident that the size and location of 60 the outlet port may be varied to correspond to different compression ratios, and that the compression ratio may be changed by shifting the position of the outlet port angularly with respect to the inlet port. This may readily be accomplished by moving the end plate 65

angularly upon the pump body, or by other convenient means. In practice, different rotors and end plates may be furnished to suit various compression ratios and conditions of use. Care should be taken, however, that the 70 cut-off edge of the outlet port 18 (just visible through the groove 19 in Fig. 2) is spaced from the line of contact of the rotor 14 with the chamber wall 11 by such an amount that the port 18 will be entirely closed before the 75 leading edge of the groove 19 passes the line of contact and establishes communication with the low pressure side of the pump, in order that there may be no flow of compressed fluid past the line of contact by way of the 80 groove from the discharge port to the low side of the pump.

The invention is not restricted to the types of pumps shown in the drawings, nor to the 85 details of construction illustrated therein, as obviously it may be applied to divers forms of rotary pumps.

I claim:

1. A rotary compressor having a chamber 90 provided with inlet and outlet ports spaced angularly with respect to each other and communicating, respectively, with inlet and outlet passages, a rotor eccentrically mounted within said chamber and contacting with its side wall between said inlet and outlet ports 95 to prevent passage of fluid therebetween, said rotor having blade means adapted to contact with the side walls of the chamber throughout the compression period subdividing the same into a plurality of compression chambers, said rotor comprising a closure for said outlet port, said rotor being provided with 100 grooves adjacent the forward side of the blade means sequentially establishing communication from the surface of said rotor to the outlet port as said rotor is revolved, said outlet port being so located in said chamber wall that communication thereto from the respective compression chambers will be 105 prevented by said rotor while the pressure within each compression chamber is being built up to substantially the pressure in the discharge passage and will be sequentially established from each chamber by the groove communication therefrom when the pressure in such chamber substantially equals the pressure in the discharge passage, whereby 110 oscillating flow of compressed fluid through said outlet port will be substantially prevented.

2. A rotary compressor having a chamber 115 provided with inlet and outlet ports spaced angularly with respect to each other and communicating, respectively, with inlet and outlet passages, a rotor eccentrically mounted within said chamber and contacting with its side wall between said inlet and outlet ports 120 to prevent passage of fluid therebetween, said rotor having blade means adapted to contact with the side walls of the chamber 125

- throughout the compression period subdividing the same into a plurality of compression chambers, said rotor comprising a closure for said outlet port, said rotor being provided with grooves adjacent the forward sides of the blade means sequentially establishing communication from the surface of said rotor to the outlet port as said rotor is revolved, the portion of said chamber wall carrying said outlet port being capable of being moved to shift the port to such locations with respect to said rotor that communication thereto from the respective compression chambers will be prevented by said rotor while the pressure within such compression chambers is being built up to substantially the particular pressure in the discharge passage and will be sequentially established from each chamber by the groove communicating therefrom when the pressure in such chamber substantially equals the pressure in the discharge passage, whereby oscillating flow of compressed fluid through said outlet port will be substantially prevented. 5 70
3. A rotary compressor having a chamber provided with inlet and outlet passages and ports spaced angularly with respect to each other, the outlet port being disposed in an end wall of said chamber, a rotor eccentrically mounted within said chamber to close said outlet port and contacting with its side wall between said inlet and outlet ports to prevent passage of fluid therebetween, said rotor having blade means adapted to contact with the side wall of the chamber throughout the compression period, said rotor closing said outlet port while the pressure within the chamber is being built up to substantially the pressure in the discharge passage, to prevent back flow of fluid into said chamber from the discharge passage, said rotor being provided with a groove positioned to uncover said outlet port when the pressure within the chamber reaches substantially the pressure in the discharge passage, for discharging the compressed fluid. 25 90
4. A rotary compressor having a chamber provided with inlet and outlet passages and ports spaced angularly with respect to each other, the outlet port being disposed in an end wall of said chamber, a rotor eccentrically mounted within said chamber to close said outlet port and contacting with its side wall between said inlet and outlet ports to prevent passage of fluid therebetween, said rotor having blade means adapted to contact with the side wall of the chamber throughout the compression period, said rotor closing said outlet port while the pressure in the compression chamber is being built up to substantially the pressure in the discharge passage, to prevent back flow of fluid into said compression chamber from the discharge passage, said rotor being provided with a groove positioned to uncover said outlet port when 50 100
- the pressure reaches substantially the pressure in the discharge passage for discharging the compressed fluid, the portion of said end wall carrying said outlet port being capable of being moved to provide for the shifting of the port to cause earlier or later opening to substantially correspond to lesser or greater ratios of compression at which the compressor may be worked. 55 105
5. A rotary compressor having a chamber provided with inlet and outlet ports spaced angularly with respect to each other, a rotor eccentrically mounted within said chamber and comprising blade means adapted to contact with the side wall of the chamber throughout the compression period, said chamber being provided with a port for the supply of lubricant under pressure, and means for covering said lubricant port during the greater part of the suction and compression cycle to prevent excessive supply and uneven distribution of lubricant to said chamber, said means providing for uncovering said lubricant port during only a small interval of time when the pressure is substantially reduced in said chamber to permit injection of a small quantity of lubricant under considerable pressure. 60 110
6. A rotary compressor having a chamber provided with inlet and outlet ports spaced angularly with respect to each other, a rotor eccentrically mounted within said chamber and comprising blade means adapted to contact with the side wall of the chamber throughout the compression period, said chamber being provided with a port for the supply of lubricant under pressure, and means carried by said rotor for covering said lubricant port during the greater part of the suction and compression cycle to prevent excessive supply and uneven distribution of lubricant to said chamber, said means providing for uncovering said lubricant port during only a small interval of time when the pressure is substantially reduced in said chamber to permit injection of a small quantity of lubricant under considerable pressure. 65 115
7. A rotary compressor having a chamber provided with inlet and outlet ports spaced angularly with respect to each other, a rotor eccentrically mounted within said chamber and comprising blade means adapted to contact with the side wall of the chamber throughout the compression period, said chamber being provided with a port for the supply of lubricant under pressure, and means carried by said rotor for covering said lubricant port during the greater part of the suction and compression cycle to prevent excessive supply and uneven distribution of lubricant to said chamber, said means providing for uncovering said lubricant port during only a small interval of time when the pressure is substantially reduced in said chamber to permit injection of a small quantity of lubricant under considerable pressure. 70 120
8. A rotary compressor having a chamber provided with inlet and outlet ports spaced angularly with respect to each other, a rotor eccentrically mounted within said chamber and comprising blade means adapted to contact with the side wall of the chamber throughout the compression period, said chamber being provided with a port for the supply of lubricant under pressure, and means carried by said rotor for covering said lubricant port during the greater part of the suction and compression cycle to prevent excessive supply and uneven distribution of lubricant to said chamber, said means providing for uncovering said lubricant port during only a small interval of time when the pressure is substantially reduced in said chamber to permit injection of a small quantity of lubricant under considerable pressure. 75 125
9. A rotary compressor having a chamber provided with inlet and outlet ports spaced angularly with respect to each other, a rotor eccentrically mounted within said chamber and comprising blade means adapted to contact with the side wall of the chamber throughout the compression period, said chamber being provided with a port for the supply of lubricant under pressure, and means carried by said rotor for covering said lubricant port during the greater part of the suction and compression cycle to prevent excessive supply and uneven distribution of lubricant to said chamber, said means providing for uncovering said lubricant port during only a small interval of time when the pressure is substantially reduced in said chamber to permit injection of a small quantity of lubricant under considerable pressure. 80 130

ity of lubricant under considerable pressure, said port and last named means being positioned so that the port, when uncovered, will discharge directly in front of the blade means.

8. A rotary compressor having a chamber provided with inlet and outlet ports spaced angularly with respect to each other, said chamber being further provided with a port for supplying lubricant under pressure, a rotor eccentrically mounted within said chamber and comprising blade means adapted to contact with the side wall of the chamber throughout the compression period, said rotor being arranged to prevent passage of fluid between said inlet and outlet ports except as it is compressed and delivered by rotation of the same, and means arranged to close said lubricant port during the greater part of the suction and compression cycle and open the same during only a small interval of time when the pressure is substantially reduced in said chamber and to close said discharge port while the fluid is being compressed to substantially the pressure of discharge and open the same only when the fluid has been compressed to substantially the pressure of discharge, substantially as and for the purpose described.

9. A rotary compressor having a chamber provided with inlet and outlet ports spaced angularly with respect to each other, said chamber being further provided with a port for supplying lubricant under pressure, a rotor eccentrically mounted within said chamber and comprising blade means adapted to contact with the side wall of the chamber throughout the compression period, said rotor being arranged to prevent passage of fluid between said inlet and outlet ports except as it is compressed and delivered by rotation of the same, and means carried by said rotor and arranged to cover said lubricant port during the greater part of the suction and compression cycle and uncover the same during only a small interval of time when the pressure is substantially reduced in said chamber and to cover said discharge port while the fluid is being compressed to substantially the pressure of discharge and uncover the same only when the fluid has been compressed to substantially the pressure of discharge, substantially as and for the purposes described.

10. A rotary compressor having a chamber provided with inlet and outlet ports spaced angularly with respect to each other; said chamber being further provided with a port for supplying lubricant under pressure; a rotor eccentrically mounted within said chamber and comprising blade means adapted to contact with the side wall of the chamber throughout the compression period; said rotor being arranged to prevent passage of fluid between said inlet and outlet ports except as

it is compressed and delivered by rotation of the same; and means carried by said rotor arranged to cover said lubricant port during the greater part of the suction and compression cycle and uncover the same during only a small interval of time when the parts are in such position that the port will discharge directly in front of said blade means and when the pressure is substantially reduced in said chamber, to inject a well distributed limited supply of lubricant directly in front of the blade means, and to cover said discharge port while the fluid is being compressed to substantially the pressure of discharge and to uncover the same only when the fluid has been compressed to substantially the pressure of discharge; substantially as and for the purposes described.

11. The rotary compressor as set forth in claim 9 further characterized in that the portion of said compressor carrying said outlet port is capable of being moved to provide for the shifting of the port to cause earlier or later uncovering of the same to substantially correspond to lesser or greater ratios of compression at which the compressor may be worked.

12. A rotary compressor comprising a body with a cylindrical bore, a circular cylindrical rotor eccentrically mounted for rotation therein, a transverse slot extending axially through said rotor, movable means mounted in said slot adapted to contact with said bore at its ends to provide a fluid tight joint, discharge and intake ports in said body, means carried by said rotor for covering said discharge port during a portion of the period of rotation before the fluid has been raised to substantially the pressure of discharge, a port for supplying lubricant under pressure to said bore, and means carried by said rotor for covering said lubricant port except during a small portion of the compression cycle when the pressure in the space adjacent the lubricating port is substantially less than the oil pressure, whereby the oil is injected in the form of a jet.

13. A rotary compressor comprising a body, a rotor eccentrically mounted for rotation therein, discharge and intake ports in said body, a port for supplying lubricant under pressure to said compressor body; and means carried by said rotor for covering said oil port during a portion of the period of rotation, said oil port being positioned to be uncovered only for a small interval when the pressure in the space adjacent the oil port is substantially less than the oil pressure, whereby the oil is injected in the form of a jet.

14. A rotary compressor having a chamber provided with inlet and outlet passages and ports spaced angularly with respect to each other, the outlet port being disposed in an end wall of said chamber, a cylindrical rotor of uniform diameter eccentrically mount-

ed within said chamber to close said outlet port and contacting with its side wall between said inlet and outlet ports to prevent passage of fluid therebetween, said rotor having blade means adapted to contact with the side wall of the chamber throughout the compression period, said rotor closing said outlet port while the pressure within the chamber is being built up to substantially the pressure in the discharge passage, to prevent back flow of fluid into said chamber from the discharge passage, said rotor being provided with a groove positioned to uncover said outlet port when the pressure within the chamber reaches substantially the pressure in the discharge passage, for discharging the compressed fluid.

15. A rotary compressor having a rotor having line contact with the side wall of its compression chamber, an outlet port in its end wall normally closed by the rotor, and a groove in the rotor for opening communication between the outlet port and the compression chamber, said outlet port being positioned with its cut-off edge so spaced from the line of contact that the port will be entirely closed before the leading portion of the groove passes beyond said line of contact.

20. In testimony whereof, I have signed my name to this specification.

25. HOLGER NIELSEN.
